UNITED STATES PATENT OFFICE.

CLINTON E. FROST, OF EAST CLEVELAND, OHIO, ASSIGNOR TO THE CLEVELAND OSBORN MANUFACTURING COMPANY, OF CLEVELAND, OHIO, A CORPORATION OF OHIO.

ROTARY BRUSH.

1,347,153.

Specification of Letters Patent. Patented July 20, 1920.

Application filed October 28, 1918. Serial No. 259,947.

To all whom it may concern:

Be it known that I, CLINTON E. FROST, a citizen of the United States, and a resident of East Cleveland, county of Cuyahoga, and State of Ohio, have invented a new and useful Improvement in Rotary Brushes, of which the following is a specification, the principle of the invention being herein explained and the best mode in 10 which I have contemplated applying that principle, so as to distinguish it from other inventions.

The present improvements, relating, as indicated, to rotary brushes, have regard 15 more especially to a brush of this type wherein the brushing material is supported so as to present a more or less cup-shape, *i. e.*, the brush section has the form, in whole or part, of a cylinder, or, more accurately, of 20 the frustum of a cone. A brush of this form I have found possesses marked utility over any other type of brush on the market, for scouring or cleaning metal castings, the brush material in such case of course being 25 strands of tempered steel wire, of such diameter as to render them quite stiff. A brush of the form indicated, when properly mounted and held on a spindle, is not only 30 extremely efficacious in cleaning smooth surfaces whether plain or curved, but also in getting around bosses and into angles, such as are found, for example, in crank case castings for motor engines, for the cleaning of which my improved brush has been found 35 admirably adapted in extensive practical use.

The invention, accordingly, consists of a novel form and construction of brush section, as also of a unique form of holder or 40 mounting therefor, whereby such section may be properly secured to a spindle, either stationary or portable, the annexed drawing and the following description setting forth in detail certain mechanism embodying the invention, such disclosed means constituting, however, but one of various mechanical forms in which the principle of the invention may be used.

In said annexed drawing:—

50 Figure 1 is a perspective view of a brush section of the improved form and construction referred to above; Fig. 2 is a plan view of a metal stamping in the form of a perfo-

rated strip utilized in the manufacture of such section; Fig. 3 is a transverse section 55 of such stamping taken on the plane indicated by the line 3—3, Fig. 2; Figs. 4 and 5 are transverse sections through the brush section, indicating the manner in which the brush material and such stamping or strip, 60 together with another component element, are assembled together; Fig. 6 is a longitudinal axial section through a brush section and holder, or mount, therefor, whereby the brush is attached to a spindle; and 65 Fig. 7 is a view similar to that of Fig. 6, but showing a modified form of brush section.

In the several figures of the drawing the brush material is shown as taking the form 70 of wire strands 1 which are preferable, as previously indicated, where the brush is to be used for rough work such as cleansing castings. Such material, however, may consist of any of the usual brush materials, being 75 folded over in loops as shown in Figs. 1, 4 and 5, which are thereupon inserted through successive apertures 2 in the stamped-up strip 3 in the fashion illustrated in Fig. 4. At the same time with the foregoing, a base 80 member, preferably consisting of a wire 4, is inserted or threaded through the successive loops until the latter are all strung thereon, following which the stamping 3 is bent along a central longitudinal axis by 85 means of a press, or otherwise, until it assumes the form illustrated in Fig. 5. The result of the foregoing operations will be to tie or press the loops of the material together beyond the base member, the bent- 90 up stamping forming a lateral support for the strands whereby their outer ends are brought more or less closely together, while at the same time said strip serves to secure the inner looped ends of the strands firmly 95 in place on the base member.

To form a brush section of the cup-shape illustrated in Figs. 1 and 2, a base member 4 and strip 3 of sufficient length, together with the requisite quantity of brush material, are assembled together in the fashion just described, and such base member and strip are thereupon bent into approximately circular form, with the strip dished or set at an angle to the plane defined by the ring 100 base, whereby the brush material is disposed 105

and held at a corresponding angle, thus giving the completed structure the form desired.

In order to attach a section of the form just described to a driving spindle 5 (whether the latter be fixed or portable is a matter of indifference), two cup-shaped clamp members 6 and 7 are utilized, both formed with central apertures adapted to fit over the reduced end 8 of the spindle, the larger outer member 6 abutting on a shoulder 9 on such spindle and being of the proper diameter and depth to inclose the base of the brush section. The inner member 7, which is of general complementary form, is thereupon forced and held in place by means of nuts 10 and 11 on the threaded end of the spindle, such inner member being formed with a peripheral shoulder 12 disposed to engage with the oppositely facing inner edge of the stamping or strip 3 that forms a part of the base of the brush section. By the foregoing means such section is terminally secured to the spindle, with its open face directed away from the latter, the shoulder on the inner member preventing any axial displacement, while the frictional engagement between the base of the section and the two members is sufficient to prevent circumferential slippage. A key 13 or equivalent device will be provided to secure the members themselves non-rotatably upon the spindle.

If desired the construction of section above described, together with clamping means of the same form may be utilized to provide a brush of disk or cylindrical form, as illustrated in Fig. 7. In such event the stranded brush material is bent outwardly at approximately right angles at a point just beyond the outer edge of the stamping, so that the material therebeyond lies in a plane at right angles to the axis of the section. The clamping means utilized to attach such section to the spindle, include an outer member 14 of substantially the same form as before, while the inner member 15 is likewise of substantially the same form, having a peripheral shoulder 16 to engage the opposed edge of the stamping, and in addition having a second shoulder or flange 17 which presses against the radially extending portion of the brush material so as to laterally support the same on one side just as the opposed edge of the other clamp member 14 supports such material on the other side.

A brush of the cup-shape illustrated in Figs. 1 and 2 obviously will have a considerably more extensive area of contact with any smooth surface, whether entirely flat or not. At the same time it can be inserted into angles and corners much more effectively than a brush of the familiar type, while by having its center clear or open it will entirely surround a boss or similar projection, and thus be able to operate not only

on the sides of the latter, but in the corners and angles thereof as well.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. As an article of manufacture, a brush section comprising a base ring, brush material looped upon said ring, and a perforated member of U-shape in cross-section laterally engaging said material, the loops of material passing through the perforations in said member and the latter being dished so as to maintain said material at an angle to the plane defined by said ring.

2. As an article of manufacture, a brush section comprising a base ring, brush material looped upon said ring, and a perforated metal stamping of U-shape in cross-section laterally engaging said material, the loops of material passing through the perforations in said stamping and the latter being dished so as to maintain said material at an angle to the plane defined by said ring.

3. The combination with a spindle, of complementary cup-shaped clamp members adapted to be terminally secured to said spindle, and a brush section comprising a base ring, brush material looped upon said ring, and a perforated member of U-shape in cross-section laterally engaging said material, the loops of material passing through the perforations in said member and the latter being dished so as to maintain said material at an angle to the plane defined by said ring, said brush section being held between said clamp members with its open face directed away from said spindle.

4. The combination with a spindle, of complementary cup-shaped clamp members adapted to be terminally secured to said spindle, and a brush section comprising a base ring, brush material looped upon said ring, and a perforated member of U-shape in cross-section laterally engaging said material, the loops of material passing through the perforations in said member and the latter being dished so as to maintain said material at an angle to the plane defined by said ring, said brush section being held between said clamp members with its open face directed away from said spindle, and said clamp members interengaging with said perforated member to secure said brush section against endwise movement.

5. The combination with a spindle, of complementary cup-shaped clamp members adapted to be terminally secured to said spindle, and a brush section comprising a base ring, brush material looped upon said

ring, and a metal stamping of U-shape in cross-section laterally engaging said material, said stamping being dished so as to maintain said material at an angle to the plane defined by said ring, and said brush section being held between said clamp members with its open face directed away from

said spindle and said inner clamp member having a shoulder adapted to engage with said stamping to secure said brush section 10 against end-wise movement.

Signed by me this 26th day of October, 1918.

CLINTON E. FROST.
